UNITED STATES PATENT OFFICE.

FRANCIS M. RICE, OF DOWS, AND ARTHUR W. HILL, OF BELMOND, IOWA.

AUTOMATIC ELECTRIC RAILWAY SWITCHING DEVICE.

No. 888,929.

Specification of Letters Patent.

Patented May 26, 1908.

Application filed September 19, 1907. Serial No. 393,711.

To all whom it may concern:

Be it known that we, FRANCIS M. RICE, a citizen of the United States, residing at Dows, in the county of Wright and State of Iowa, and ARTHUR W. HILL, a citizen of the United States, residing at Belmond, in the county of Wright and State of Iowa, have invented a new and useful Improvement in Automatic Electric Railway Switching Devices, of which the following is a specification.

Our invention relates to an automatic electric railway switching device, designed more particularly for trolley lines, but applicable also to other uses.

Electro-mechanical devices have already been applied to a car which through the adjustment of a crank handle, by the motor-man, projected a powerful electro-magnet into such relation to the switch tongue in the track as to move it laterally to open the switch and turn the car out upon a siding, or on to a branch line, an example of this being shown in the patent to E. J. Rice, No. 850,604, April 16, 1907. In such switch operating device the switch when opened is left open after the car has passed on to the siding or branch line, leaving a dangerous condition in the main line of an open switch which prevents through travel on the main line and involves the danger of collision as well as an embarrassment of traffic.

Our invention is an improvement upon this switch operating device and its object is to secure the automatic closing of the switch after the car has passed on to the siding or branch line.

To this end our invention consists in novel electro - mechanical devices whereby the switch opening devices at the front end of the car are connected to switch closing devices located on the rear end of the car, both being so coördinately related that the adjustment of the one set of devices for opening the switch simultaneously and by the same movement brings into proper position the switch closing devices at the rear end of the car, so that the car passes on to the siding and in leaving the main line immediately restores in an automatic manner its continuity for through travel. Several different forms of mechanism for accomplishing these results are provided which will be hereinafter more fully described with reference to the drawings, in which

Figure 1 is a plan view of a switch and track rails showing in diagrammatic position

the truck and electro-magnets of the car in the act of entering the switch. Fig. 2 is a plan view of the platform of a car, partly broken away at the ends and showing its attachments in position for switching. Fig. 2^a is a fragmental view of one end of the same, showing the attachments in the neutral position. Fig. 3 is an end view of the switch opening devices at the forward end of the car. Fig. 4 is a similar view of the switch closing devices at the rear end of the car. Fig. 5 is a detail in perspective of the circuit closing devices. Fig. 6 is an inverted plan view, showing a modification of the switch operating devices. Fig. 6^a is an enlarged end view of the devices shown in Fig. 6. Fig. 7 is an end view showing a still further modification and Fig. 7^a is a track, illustrating the operation of the form of the device shown in Fig. 7.

Referring to Fig. 1, A A represent the rails of the main line and B B the rails of a branch line or siding.

C is a switch tongue pivoted on a vertical axis at p and arranged to be swung horizontally about the same either in the direction of the full line arrow a or the dotted line arrow a. When thrown in the direction of the full line arrow a, as shown in full lines, the switch is open and connects the right hand part of the main line A A with the siding or branch rails B B and when thrown in the direction of the dotted line arrow a it makes a continuous connection of the right hand rails of the main line with the left hand rails of the main line, connecting the main line for through travel.

D represents the front and D' the rear trucks of a car, which car carries at its forward end, some distance in front of the front trucks, two electro-magnets E E, and also carries in rear of the rear trucks two other electro-magnets E' E'. These electro-magnets are suspended beneath the car and are connected to it by hanger bars, as hereinafter described, and are capable of adjustment transversely across the rails, so as to occupy a position outside of the rails or inside of the rails, or in a vertical plane immediately above the rails. Said electro-magnets extend down to close proximity to the rails so as to be within the range of attractive influence on the switch tongue C, and they throw said switch tongue horizontally in the direction of the full arrow a, or dotted arrow a, according to the position of the electro-magnets.

net. If the electro-magnet is inside the tongue C, it throws it in the direction of the full line arrow *a*, and if the electro-magnet is outside the tongue C, it throws the tongue in the direction of the dotted arrow *a*. To avoid confusion, we have, in Fig. 1, only shown the electro-magnets diagrammatically, to indicate their position. It will also be perceived that we have shown two front 5 electro-magnets E E and two rear electro-magnets E' E'. The purpose of this duplication is merely to provide for sidings or branch lines on either side of the main line, or to permit the car to be run either forward 10 or backward and still operate the switch. For the purposes of illustrating our invention it will be sufficient to consider only one front and one rear electro-magnet on the same side of the car, as these two are the co-operating 15 ones for switching on one side of the main line. So far as the action of the front electro-magnets are concerned these are used for opening the switch and have already been employed. It will be seen, however, that if 20 the switch C is opened in the direction of the full arrow *a* by the passage of the front electro-magnets, and the switch is not closed afterwards, the main line will be left open, with results that would be embarrassing, or 25 even disastrous.

Our invention provides the rear electro-magnets E' E' and so connects them with the operating mechanism of the front electro-magnets, as hereafter described, as to not 30 only automatically open the switch and turn the car on to the siding, as has been heretofore done, but also immediately, when leaving the switch, to close it again behind the car and restore the continuity of the main line. The 35 means by which this is accomplished will now be described.

Referring to Figs. 2, 3 and 4, X represents the floor of a car. On the forward end of the same is arranged, see Fig. 3, a vertical manually operated shifting shaft F having at the 40 upper end a crank handle *f* for rocking the same and having at its lower end, beneath the car floor, a crank *g* connected to a sectional cross bar G which cross bar is pivoted 45 to and connects the two hanger bars H H carrying on their lower ends the front pair of electro-magnets E E. The vertical operating shaft F rises above the car floor to a convenient position for the motorman to operate 50 the handle *f* and the upper end of such shaft is arranged to turn freely in bearings in an upright frame f', and three stop seats s' s' s' are provided for holding the crank handle in 55 its right position, its left position, or in neutral position between the two.

At the rear end of the car, Figs. 2 and 4, the electro-magnets E' E' are similarly connected by a pivoted cross bar G' and the cross bar is connected to a crank arm g' on 60 the lower end of a short vertical shaft F'

turning in bearings in the car floor. This shaft F' may extend only to the car floor as shown, or it may go above the same and be equipped with the same crank handle and other devices for its manual operation if desired. As cars are usually run with the motorman always at the same end, it is not necessary to have the second operating handle in the rear.

The two sets of adjusting devices for the front and rear electro-magnets are simultaneously connected and operated as follows. A long slide rod J extends longitudinally beneath the car floor from end to end. At one end it is pivotally connected to a horizontal 70 and transversely arranged lever K fulcrumed to an offset from the body of the car, and at the other end it is pivotally connected to a similar lever K'. The other end of lever K is connected by a link *j* to a rigid crank arm *i* on the operating shaft F, and the corresponding end of lever K', at the other end of the car, is connected by a link *j'* to a rigid crank arm *i'* on the vertical shaft F'. This furnishes mechanical means whereby the swinging of the front electro-magnets to one side of the track will simultaneously, and by the same movement, swing the rear set of electro-magnets to the other side of the track.

Assuming that the car shown in Fig. 2 is 95 going to the left, when the manually operated shaft F is turned to throw the front electro-magnets E E, to the position shown in Figs. 2 and 3, this same movement also throws the rear electro-magnets to the position shown 100 in Figs. 2 and 4 and these positions of the front and rear electro-magnets are the same as those shown diagrammatically in Fig. 1, in which the front electro-magnets have pulled the switch tongue in the direction of 105 full line arrow *a* and have sent the front trucks D on to the siding and in which the position of the rear electro-magnet E' is ready to pull the switch tongue in the direction of the dotted arrow *a* when it reaches 110 the switch, so as to automatically close the main line for through travel.

When an electro-magnet exerts its pull upon the switch tongue it has a tendency to lift said tongue as well as move it sidewise. 115 This lifting of this tongue is prevented by a cross bar *c*, Fig. 1, which is fixed to the tongue C on its lower side and moves with it, and the ends of which cross bar slide under the main rail and guard rail and are thereby held 120 down with the tongue, so that while the latter cannot rise, it may move freely from side to side.

We will now describe the electrical connections whereby the electro-magnets are 125 energized by the same movement of adjusting them for switching reference being had to Figs 2, 2^a and 5.

It will be understood, that our invention is applicable either to the overhead trolley sys- 130

tem or the underground system, it being only necessary to place the operating circuit hereafter described any where within the path of the motor circuit or the circuit of a storage battery.

In Fig. 2 the current comes (from the trolley for instance) to the point 1 and thence by wire 2 to a double contact 3. 3. between the two arms of which plays the stem *h* on the horizontally adjustable cross bar *G*. From cross bar *G* a wire 4 leads to the coil of one electro-magnet *E* and thence by wire 5 to the coil of the other electro-magnet *E*, thence by wire 6 to the other end of the car and through electro-magnet *E'* and wire 7 to the other electro-magnet *E'* and by wire 8 to the car wheel where it is grounded through the rail. It will be seen therefore in any extreme movement of the cross bar *G* to either the right or left the contact arm *h* will touch one side or the other of the double contact 3—3 and complete the circuit through the above named path, energizing the electro-magnets by the same movement which adjusts them to the position for switching. When the crank handle *f*, Fig. 3, is adjusted to the middle seat *s*², then the contact arm *h* is midway between the two contacts 3—3 and does not touch either, as seen in Fig. 2^a, and the current is therefore broken and the magnets are not energized. In this neutral position of parts the electro-magnets lie in a vertical plane immediately above the main rails and produce no effect on the switches.

It will be understood that the electro-magnets are to be constructed with such size of wire, number of coils and length of cores, as to suit the voltage of the lines and to furnish a sufficient moving power to positively and surely adjust the switch.

In the form of our invention so far described, the lateral shifting of the electro-magnets is a manual operation, the shifting being done by the strength of the motor-man's arm transmitted mechanically. As a modification of our invention, we may effect the swing of the electro-magnets by electric power by the mere adjustment of an electric switch as shown in Figs. 6 and 6^a. In this case the adjusting cross bar *G* for the electro-magnets has an armature *N* playing between the poles of two powerful electro-magnets *M* and *M'*, as seen in Fig. 6^a, the electro-magnets *M* *M'* being in the same circuit with the switch shifting electro-magnets *E* *E'*. The connections are made as seen in Fig. 6. When the switch arm *O* is on the contact *n* current flows through wire 10, magnet *M*, wire 11, magnet *E*, wire 12, to the opposite end and opposite side of the car, to magnet *M'*, wire 13, magnet *E'* and the car wheel to ground. The magnets *M* and *M'* are thereby energized and *M* pulls the electro-magnets *E* at the front of the car to one side, while *M'*, at the rear of the car, pulls the electro-mag-

net *E'* in the opposite direction. If the switch *O* be placed upon the contact *m* the electro-magnets *E*, *M'* and *E'* *M*³ are energized, and when the switch is in the neutral position, as shown in Fig. 6, none of the electro-magnets are energized. 70

As a still further modification of our invention we may dispense with the movement of the electro-magnets *E* and *E'* altogether, and make the switch adjusting magnets stationary, as shown in Figs. 7 and 7^a. 75

When the stationary electro-magnets are used, they are fixed under the car in a rigid frame, see Fig. 7, composed of hanger bars *R* *R* and a cross bar *Q* firmly braced to resist 80 the pull of the magnets. The front electro-magnets *E*² are permanently arranged inside the rails, as shown in Figs. 7 and 7^a, and serve to open the switch, and the rear electro-magnets *E*³, shown in Fig. 7^a, are fixedly 85 arranged in a corresponding rigid frame outside of the rails. When the current is shown through one front electro-magnet and one rear electro-magnet, on the same side of the car, it will be seen that the front electro-magnet opens the switch and the rear one 90 closes it in the manner heretofore described.

In making use of our invention we do not confine ourselves to the particular construction and arrangement of parts shown and described, as these may be varied in many respects without departing from the scope of our invention as set forth in the claims. 95

We claim

1. A switch operating mechanism, consisting of a car, electro-mechanical devices carried on the front end of the car for swinging the switch tongue in one direction to open it, electro-mechanical devices carried on the rear end of the car for swinging the switch 100 tongue in the other direction to close it, and a circuit closer for throwing an electric current through the electro-magnets of both said devices. 105

2. A switch operating mechanism, consisting of a car, two electro-magnets suspended beneath the car at its front and back ends respectively and made adjustable transversely to the car and rails, means for adjusting these electro-magnets simultaneously in 115 opposite directions and means for throwing an electric current through the same. 110

3. A switch operating mechanism, consisting of a car, two electro-magnets suspended beneath the car at its front and back ends respectively and made adjustable transversely to the car and rails, mechanical means for connecting the two electro-magnets, means for the manual operation of the two electro-magnets in opposite directions and means 120 for throwing an electric current through said electro-magnets. 125

4. A switch operating mechanism, consisting of a car, two electro-magnets suspended beneath the car at its front and back ends re- 130

spectively and made adjustable transversely to the car and rails, means for adjusting these electro-magnets simultaneously in opposite directions and means for throwing an electric current through the same by the same movement which adjusts the electro-magnets transversely.

5. A switch operating mechanism, consisting of a car, two electro-magnets suspended beneath the car at its front and back ends respectively and made adjustable transversely to the cars and rails, mechanical means for connecting the two electro-magnets, means for the manual operation of the two electro-magnets in opposite directions and means for throwing an electric current through said electro-magnets by the same movement which adjusts the electro-magnets transversely.

20 6. A car having two reversely moving electro-magnets extending down to close proximity to the rails, means for moving them transversely to the car and means for connecting them for simultaneous movement in opposite directions to successively open and close a switch tongue.

7. A car having two reversely moving electro-magnets extending down to close proximity to the rails, means for moving them transversely to the car, means for connecting them for simultaneous movement in opposite directions to successively open and close a switch tongue, and an electric circuit closer arranged to close a circuit through the electro-magnets when moved to their extreme positions.

35 8. The combination with the track rails;

of a laterally adjustable switch tongue having a cross piece attached to it and moving with it and extending under the rails and a switch operating device carried by the car and comprising a superposed electro-magnet arranged to act upon the switch tongue and shift it laterally by magnetic attraction.

9. A switch operating mechanism, consisting of a car, two electro-magnets suspended beneath the car at its front and back ends respectively, hanger bars carrying the same and hinged to the car to swing transversely, a longitudinally sliding rod with connections at its opposite ends for swinging the hanger bars, a vertical and manually operated shaft connected at its lower end to the hanger bars and connecting slide rod and having an operating handle at its upper end.

10. A switch operating mechanism, consisting of a car, two electro-magnets suspended beneath the car at its front and back ends respectively, hanger bars carrying the same and hinged to the car to swing transversely, a longitudinally sliding rod with connections at its opposite ends for swinging the hanger bars, a vertical and manually operated shaft connected at its lower end to the hanger bars and connecting slide rod and having an operating handle at its upper end, and an electric circuit closer under the control of said manually operated shaft.
